CLAIM

[21] Appl. No.: 53,957

The ornamental design for a decorative environmental aroma machine, as shown and described.

[22] Filed: May 2, 1996

DESCRIPTION

[51] LOC (6) Cl. 23-04

FIG. 1 is a front right side, top perspective view showing our new design;

[52] U.S. Cl. D23/367; D23/366

FIG. 2 is a front elevational view thereof, the rear being a mirror image of that shown;

[58] Field of Search D23/366-369; D21/253, 114; D9/414, 322; 220/676; 239/211, 58, 55, 47, 44, 60, 57, 56, 54, 34, 59; 261/DIG. 65; 392/390, 386, 394, 395, 403-406; D25/26,

FIG. 3 is a left side elevational view thereof, the right side being a mirror image of that shown;

FIG. 4 is a top plan view thereof; and,

FIG. 5 is a bottom plan view thereof.

The broken line showing of environmental structure in FIGS. 2-5 is for illustrative purposes only and forms no part of the claimed design.
